United States Patent Office.

DENNIS C. WILCOX, OF WEST MERIDEN, CONNECTICUT, ASSIGNOR TO
MERIDEN BRITANNIA COMPANY.

Design No. 2,741, dated August 6, 1867.

DESIGN FOR THE HANDLE OF A FORK OR SPOON.

The Schedule referred to in these Letters Patent and making part of the same.

TO ALL WHOM IT MAY CONCERN:

Be it known that I, DENNIS C. WILCOX, of West Meriden, county of New Haven, and State of Connecticut, have invented or produced a new and original Pattern or Design for a Handle for Forks, Spoons, Ladles, &c.; and I do hereby declare that I believe the following to be a clear and exact description thereof, reference being had to the accompanying photograph, in which—

a is a configurated handle, embellished with alternate elevations and depressions, peculiarly adapted for handles for forks, spoons, ladles, and other like utensils.

What I claim, therefore, and desire to secure by Letters Patent, is—

The design or pattern for handles for forks, spoons, ladles, and other like utensils, substantially as shown and described.

DENNIS C. WILCOX. [L. S.]
